REFRIGERATING APPARATUS

Alex A. McCormack, Dayton, Ohio, assignor to
Frigidaire Corporation, Dayton, Ohio, a cor-
poration of Ohio

Application August 30, 1930, Serial No. 478,959
Renewed November 3, 1932

9 Claims. (Cl. 62—115)

This invention relates to refrigerating appa-
ratus of the compression type, and more particu-
larly to motor-compressor-condenser units for
use in refrigerating apparatus of such type.

One of the objects of the present invention is
to provide improved means for supplying lubri-
cant to moving elements of the compressor mech-
anism from a reservoir and to return said lubri-
cant to said reservoir.

Another object is to arrange the aforesaid
means in such a manner that lubricant in any
appreciable amount is prevented from being cir-
culated throughout the refrigerating system.

Another object is to provide a gas tight casing
for housing the compressor and its driving motor
and to employ said casing for storing a quantity
of liquid refrigerant and a quantity of lubricant.

Further objects and advantages of the present
invention will be apparent from the following
description, reference being had to the accom-
panying drawings, wherein a preferred form of
the present invention is clearly shown.

In the drawings:

Fig. 1 is a view, partly in cross section and
partly diagrammatic, of a refrigerating apparatus
embodying features of my invention;

Fig. 2 is a view in cross section of a portion
of the apparatus shown in Fig. 1, the view being
taken on the line 2—2 of Fig. 1; and

Fig. 3 is a fragmentary view in cross section
taken along the line 3—3 of Fig. 2.

Heretofore in refrigerating compressing units
of the sealed-in type, difficulty has been en-
countered for the reason that where a casing
encloses the compressor and motor and is pro-
vided with an outside condenser, a slight amount
of refrigerant is condensed in the casing before
the gaseous refrigerant reaches the condenser.
Where a body of oil is provided in the bottom
of this casing for the lubrication of the appa-
ratus, the refrigerant thus condensed flows to
the body of oil and gradually builds up such a
large body of liquid refrigerant that the oil is
displaced from its normal position in the casing
and is thus prevented from circulating to the
moving parts of the mechanism. According to
this invention, this and other difficulties are
avoided by providing a sump in the casing of
sufficient capacity and correct design, that all of
the liquid refrigerant condensed in the casing and
also in the outside condenser itself can be dis-
charged into the sump where the liquid refrig-
erant and the lubricant maintain their proper
zones for the proper operation of the mechanism.

The liquid refrigerant from this sump is then

circulated through the evaporator and returned
in an evaporated condition to the regular inlet of
the compressing unit.

Referring to the drawings, the numeral 20
designates in general a motor compressor unit 60
comprising a gas tight casing 21 which forms a
compression chamber 22 in which is located a
compressor 24 and a driving motor 25 operatively
connected with said compressor by means of a
shaft 28. The compressor is adapted to supply 65
liquid refrigerant to an evaporator 30 for provid-
ing refrigeration at a desired place. The com-
pressor withdraws the gaseous refrigerant from
the evaporator through a conduit 32, compresses
the gaseous refrigerant and delivers it to an out- 70
side condenser 35, preferably air cooled, through
an outlet passage 37 provided in the gas space of
the compression chamber 22. The condenser 35
condenses the gaseous refrigerant and delivers it
to a reservoir or sump 40 formed in the bottom 75
of the casing 21. The reservoir 40 provides a
receiver for storing a body of liquid refrigerant.
For the purpose of illustration I have indicated
the liquid refrigerant level at 42. The reservoir
40 also provides a storage space for a body of 80
lubricating oil used for lubricating moving ele-
ments of the compressor in a manner hereinafter
described. For the purpose of illustration I have
shown the level of lubricating oil at 45. The
motor compressor unit delivers liquid refrigerant 85
from the reservoir 40 to the evaporator 30 under
the control of an expansion valve 47 through a
supply conduit 49 having a connection 50 with
the casing 21 below the level of liquid refrigerant.
A thermostat 52 is connected to the rear end of 90
the evaporator and is operatively connected to
a switch 55. The switch 55 connects the motor
25 with the power mains 58 and is arranged for
controlling the starting and stopping of the motor
25 in response to the temperature of the evap- 95
orator 30. A motor driven fan 60 for cooling the
condenser 35 is connected in parallel with the
motor 25 and is controlled by the switch 55.

Referring more in detail to the drawings, the
casing 21 is formed in three parts, namely, a 100
lower member 62, an intermediate member 64 and
a top member 65. The lower member 62 is pro-
vided with an upwardly extending boss 67 having
a bore 68 which receives a bushing 69 which pro-
vides a bearing 70 for the lower end of the shaft 105
28. The intermediate member 64 is provided
with an integrally formed inwardly extending
portion 72 which provides a bearing surface 74
for the upper part of the shaft 28. The portion
72 permits communication between the lower 110

and intermediate members through one or more openings 76. The lower and intermediate portions are secured together by screws 78 and the top member 65 is secured to the intermediate member by screws 80. Suitable gasket material is provided between the joints of the members 62, 64 and 65 to thus provide a gas tight or hermetically sealed casing.

The motor 25 for driving the compressor 24 comprises a rotor 85 and a stator 86. The compressor 24 comprises in general a cylinder 90 secured to the boss 67 by screws 91. An oscillating sleeve 94 is adapted to be actuated within the cylinder 90 for compressing the gas. The sleeve 94 is adapted to be actuated by an eccentric 97 formed integrally with the shaft 28. The compressor is provided with an inlet passage 100 which extends through boss 67 and the wall of the sleeve 90 and leads to the compression space 15 of the compressor. An outlet passage 102 leads to the compression chamber 22 whence the compressed gas passes through the outlet passage 37 provided in the top member 65 of the casing 21 to a condenser 35. Preferably the outlet passage 37 is provided with a check valve 106 which permits the gas to pass therethrough but prevents return thereof.

In order to provide means for lubricating the moving elements of the compressor I have provided a lubricant pump 110 of the eccentric type. The pump is provided with an inlet passage 112 located below the level of lubricant and above the level of liquid refrigerant. The pump 110 is adapted to build up a pressure in the space 115 formed in the boss 67 and to force the lubricant through a passage 120 formed in the central portion of the shaft 28 whence the lubricant is delivered to lateral ports 122, 123, 124, 125 and 126 in said shaft. The ports 122 and 123 serve to supply lubricant to the bearing 70 and the ports 124 and 125 deliver lubricant to the sleeve 94 while the port 126 allows lubricant to flow to the bearing 74. The lubricant thus circulated will return to the reservoir 40 by gravity.

In the present embodiment I have shown the liquid refrigerant as having a heavier specific gravity than the lubricant. It is to be understood however, that the lubricant could be located below the liquid refrigerant by providing a liquid refrigerant of lighter specific gravity than the lubricant and by simply changing the position of the pump inlet 112 and the liquid refrigerant outlet 50.

In an apparatus of the type herein described there are many advantages some of which are that lubricant and liquid refrigerant are stored in the motor compressor casing and that the lubricant which is used for lubricating moving elements of the system is prevented from entering the refrigerating system in any appreciable amount, and this is accomplished by providing the liquid refrigerant outlet on the casing below the level of liquid refrigerant and by connecting the condenser 35 in parallel with the casing 21. Thus, if lubricant should pass through the outlet 37 it would be returned to the reservoir through the condenser 35, and only such lubricant as might be dissolved in the liquid refrigerant would be circulated through the evaporator.

While the form of embodiment of the invention as herein disclosed, constitutes a preferred form, it is to be understood that other forms might be adopted, all coming within the scope of the claims which follow.

75 What is claimed is as follows:

1. Refrigerating apparatus comprising in combination a casing, a compressor within said casing, a motor for driving said compressor within said casing, said casing providing a reservoir for a body of lubricating oil and for a body of liquid refrigerant, a condenser located outside said casing and having a connection with said casing for condensing the gaseous refrigerant discharged by said compressor and for delivering the condensed refrigerant to said reservoir, an evaporator connected on one end thereof to the liquid refrigerant space in said casing and its other end leading to said compressor and means for delivering said lubricant to said compressor and returning said lubricant to said reservoir. 80

2. Refrigerating apparatus comprising in combination a casing, a compressor within and discharging into said casing, a motor for driving said compressor within said casing, said casing providing a reservoir for a body of lubricating oil and for a body of liquid refrigerant, a condenser located outside said casing and having one end thereof connected to the gas space in said casing and its other end connected to said casing and leading to said reservoir for condensing the gaseous refrigerant discharged by the compressor into said casing and delivering it to said reservoir, an evaporator connected on one end thereof to the liquid refrigerant space in said casing and its other end leading to said compressor and a lubricating system for delivering lubricant to said compressor and returning said lubricant to said reservoir. 95

3. Refrigerating apparatus comprising in combination a casing, a compressor within and discharging into said casing a motor for driving said compressor, said motor being located in said casing, said casing providing a reservoir for a body of lubricating oil and for a body of liquid refrigerant, a condenser located outside said casing and having one end thereof connected to the gas space in said casing and its other end connected to said casing below the level of refrigerant in said reservoir, an evaporator connected on one end thereof to the liquid refrigerant space in said casing and its other end leading to said compressor and means for delivering said lubricant to said compressor and returning it to said reservoir. 100

4. Refrigerating apparatus comprising in combination a casing, a compressor within said casing, a motor for driving said compressor, said motor being located in said casing, said casing providing a reservoir for a body of lubricating oil and for a body of liquid refrigerant, a condenser located outside said casing and having one end thereof connected to the gas space in said casing and its other end connected to said casing below the level of refrigerant in said reservoir, an evaporator connected on one end thereof to the liquid refrigerant space in said casing and its other end leading to said compressor and a lubricant pump having an inlet below the level of lubricant in said casing for delivering said lubricant to said compressor and returning it to 115 said reservoir. 120

5. Refrigerating apparatus comprising in combination a casing, a compressor within said casing, a motor for driving said compressor, said motor being located in said casing, said casing providing a reservoir for a body of liquid refrigerant and for a body of lubricant, one of said liquids being of a heavier specific gravity than the other, a condenser located outside said casing and having a connection with said casing for 130

condensing the gaseous refrigerant discharged by said compressor and for delivering the condensed refrigerant to said reservoir, an evaporator connected on one end thereof to the liquid refrigerant space in said casing and its other end leading to said compressor and means for delivering said lubricant to said compressor and for returning it to said reservoir.

80

6. Refrigerating apparatus comprising in combination a casing, a compressor within said casing, a motor for driving said compressor, said motor being located in said casing, said casing providing a reservoir for a body of liquid refrigerant and for a body of lubricant, said liquid refrigerant being of a heavier specific gravity than said lubricant, a condenser located outside said casing and having one end thereof connected to the gas space in said casing and its other end connected to said casing below the level of liquid refrigerant therein, an evaporator connected on one end thereof to the liquid refrigerant space in said casing and its other end leading to said compressor and means for delivering said lubricant to said compressor and for returning it to said reservoir.

85

7. Refrigerating apparatus comprising in combination a casing, a compressor within said casing, a motor for driving said compressor in said casing, said casing providing a reservoir for a body of lubricant and a body of liquid refrigerant, said liquid refrigerant being of a heavier specific gravity than said lubricant, a condenser located outside said casing and having a connection with said casing for condensing the gaseous refrigerant discharged by said compressor and for delivering the condensed refrigerant to said reservoir, an

90

8. Refrigerating apparatus comprising a motor-compressor-condenser unit and an evaporator in refrigerant circulating relationship, said motor-compressor-condenser unit comprising a casing, a compressor within said casing, a motor within said casing driving said compressor, and a condenser located outside said casing and having one end thereof connected to the gas space in said casing and having its other end in open communication with said casing, and returning lubricant from said condenser to said casing, an evaporated refrigerant line delivering evaporated refrigerant from said evaporator to said unit, and a liquid refrigerant line delivering liquid refrigerant from said unit to said evaporator.

95

9. Refrigerating apparatus comprising a motor-compressor-condenser unit and an evaporator in refrigerant circulating relationship, said motor-compressor-condenser unit comprising a casing, a compressor within said casing, a motor within said casing driving said compressor, and a condenser located outside said casing and having one end thereof connected to the gas space in said casing and having its other end in open communication with said casing, in which condenser all of the condensation of said refrigerant normally takes place and from which said other end the lubricant discharged from said casing into said condenser is returned.
